UNITED STATES PATENT OFFICE.

WILLIAM A. ZEIDLER, OF NEW YORK, N. Y.

SPIRAL FOR SHELLS.

1,368,981.

Specification of Letters Patent. Patented Feb. 15, 1921.

Application filed April 24, 1918. Serial No. 220,545.

To all whom it may concern:

Be it known that I, WILLIAM A. ZEIDLER, a citizen of the United States, residing at New York, in the county of New York and 5 State of New York, have invented certain new and useful Improvements in Spirals for Shells, of which the following is a specification.

The object of my invention is to provide 10 a spiral for locking the detonating mechanism of an explosive shell, comprising a spirally wound strip of flexible material having a folded over and interlocked outer end portion forming a weight attached to 15 the body of the strip, whereby when the shell is fired the weight is thrown outwardly by centrifugal force and the spiral is unwound and wholly detached from the shell.

The accompanying drawings illustrate a 20 practical embodiment of the invention wherein Figures 1 and 2 are fragmentary sectional views illustrating the operation of rolling down the stock from which the strips are made; Fig. 3 is an illustration of 25 the stock in plan and edge views; Fig. 4 is a combined plan and longitudinal sectional view of the thickened weighted end of the strip before it is doubled upon itself; Fig. 5 is a combined plan and edge view of the 30 relatively thin spacer-holding inner end of the strip; Fig. 6 is a detail view of the spacer elements; Fig. 7 is a view of the completed spiral applied to a detonating pin, the latter appearing in section; Fig. 8 is a longitudinal 35 sectional view of the weighted, doubled end of the strip; Figs. 9 and 10 are two views of an explosive shell, the first, showing the safety lock or spiral in place on the detonating pin or plunger, and the 40 second showing the latter freed from the restraint of the spiral.

In Fig. 9, the spiral or safety lock, is indicated at 15, in its normal operative position, holding the detonating pin 16 of the 45 shell 17 in its projected "safe" position. This spiral preferably is made as follows:

A piece of stock 18, of brass or other material, is by means of rollers 19, 20, or the like, formed with a thickened end portion 50 21 and a reduced or thinned body portion 22. In the illustration this is accomplished by providing a cutaway 23 in one of the rollers to leave space for the thickened head portion of the blank (Fig. 1), the following roller surfaces coming closely together

(Fig. 2) for the purpose of reducing the remainder of the blank. The stock may originally be of the thickness desired for the heavier thick portion of the blank, as shown (Fig. 1), in which case the rolling 55 action will simply result in reducing the main body portion of the blank. The blank is then severed longitudinally along the lines 24 into strips of the requisite width for the spirals. Slots 25 of limited longitudinal extent are punched in the thickened ends of the strips and rivet lugs 26 are struck up from such thickened portions at points farther removed from the ends, said lugs being engaged in the slots 25 and headed 60 or riveted over as shown at 27 in Fig. 8 for integrally holding these end portions together when they are doubled over and interlocked upon each other, as indicated in 65 this view. The strips are then coiled into 70 spiral form with the thinned and more flexible portion at the inside of the coil and the thickened weighted portion at the outside 75 of the coil as shown in Fig. 7. Spacer elements, such as those indicated at 28, 29, are 80 usually employed for performing the actual locking function, these elements being made of hardened steel and being of the requisite length to hold the detonating pin 85 in its non-firing position. These elements are shown made as semi-cylindrical segments about which the strip is coiled. One of the segments also is shown provided with a pin or key 30, taking into a keyway 31 formed in the shank of the detonating pin, 90 said key projecting through an opening 31 in the inner end portion of the strip and thus in effect keying the inner end of the spiral to the detonating pin so as to cause 95 it to rotate therewith. The strips may be 100 shaped as indicated at 32, 33, at their inner ends to form seats for the spacer elements, and when the spiral is made up it may be bound together by a temporary fastener such as the encircling wire 34.

When the shell is ready to be placed in the gun this binding may be removed and the spiral will then be free to unwind when the shell is fired. The weight on the outer end of the spiral strip flies outwardly owing 105 to the centrifugal force due to the rapid rotation of the shell and, as it forms a part of the strip it does not break away therefrom and positively insures that the strip will unwind properly to detach itself and 110

release the detonating pin. This leaves the said pin then free to be operated upon contact with a solid object, it being customary to provide in shells of this character a weak 5 pin 35 for lightly retaining the detonating pin in such position and which will be sheared off when the head of the detonating pin strikes a solid.

The rivet for securing together the doubled-over ends of the strip is struck up 10 from the thickened part of the strip and so can be made as strong as necessary. The slot 25 is made long enough to allow for the unequal movements of the inner and outer 15 layers as the doubled-over end portions are bent to their final curved shape, as indicated in Fig. 8.

While I have shown and described one embodiment of my invention, it is obvious 20 that it is not restricted thereto, but that it is broad enough to cover all structures that come within the scope of the annexed claims.

I claim:

1. A spiral for locking the detonating 25 mechanism of an explosive shell, comprising a spirally wound strip of flexible material having a folded over and interlocked outer end portion forming a weight attached to the body of the strip, whereby when the shell 30 is fired the weight is thrown outwardly by centrifugal force and the spiral is unwound and wholly detached from the shell.

2. A spiral for locking the detonating mechanism of an explosive shell, comprising 35 a spirally wound strip of flexible material having the outer end portion thereof folded over and interlocked to form an end which is heavier than the balance of the strip.

3. A spiral for locking the detonating 40 mechanism of an explosive shell, comprising a spirally wound strip of flexible material having the outer end portion thereof doubled back upon itself to form an integrally attached weight.

4. A spiral for locking the detonating mechanism of an explosive shell, comprising 45 a spirally wound strip of flexible material having the outer end portion thereof doubled back upon itself to form an integrally attached weight and means for secur-

ing together said doubled-over weight-forming end portions of the strip.

5. A spiral for locking the detonating mechanism of an explosive shell, comprising a spirally wound strip of flexible material 55 having the outer end portion thereof doubled back upon itself to form an integrally attached weight and a rivet fastening said doubled-over portions together and formed integrally with one of said portions. 60

6. A spiral for locking the detonating mechanism of an explosive shell, comprising a spirally wound strip of flexible material having the outer end portion thereof doubled back upon itself to form an integrally attached weight, one of said doubled-over portions having a longitudinal slot 65 therein and a rivet stud on the other of said portions engaged in said slot.

7. A spiral for locking the detonating 70 mechanism of an explosive shell, comprising a spirally wound strip of flexible material having an outer end portion thereof doubled back upon itself to form an integrally attached weight, the inner one of said 75 doubled-over portions having an integral upstanding rivet lug and the outer of said portions having a longitudinal slot receiving said rivet lug.

8. A spiral for locking the detonating 80 mechanism of an explosive shell, comprising a spirally wound strip of flexible material having a heavier portion at the outer end thereof doubled back upon itself.

9. A spiral for locking the detonating 85 mechanism of an explosive shell, comprising a spirally wound strip of flexible material having a thickened outer end portion doubled back upon itself.

10. A spiral for locking the detonating 90 mechanism of an explosive shell, comprising a spirally wound strip of flexible material having a heavier portion at the outer end thereof doubled back upon itself and an integral rivet struck up from one of said relatively thick doubled-over end portions engaged with the other doubled-over thick portion.

In testimony whereof I affix my signature.
WILLIAM A. ZEIDLER.
